UNITED STATES PATENT OFFICE.

GEORGE W. SPALDING, OF WORCESTER, MASSACHUSETTS, ASSIGNOR, BY MESNE ASSIGNMENTS, TO MILLS BELT COMPANY, OF WORCESTER, MASSACHUSETTS, A CORPORATION OF MASSACHUSETTS.

LOOM TAKE-UP MECHANISM.

Application filed June 25, 1920. Serial No. 391,731.

To all whom it may concern:

Be it known that I, GEORGE W. SPALDING, a citizen of the United States, residing at Worcester, in the county of Worcester, State 5 of Massachusetts, have invented a certain new and useful Improvement in Loom Take-Up Mechanisms, of which the following is a specification, reference being had therein to the accompanying drawings.

10 The invention is intended for application to looms used for producing webs comprising a section wherein a given number of warp-threads is interwoven and a succeeding section in which fewer than the whole of such number are interwoven, or vice versa. An example of the webs which my invention is designed to assist in producing is a web composed of alternate wide sections and narrow sections succeeding one another in the 15 length of the web, as for instance in the case of some webs which are employed in the manufacture of suspenders and braces.

20 The general object of the invention is to enable a material economy to be effected, and much of the waste heretofore customary to be avoided, in the case of the warp-threads which are used in weaving the section containing the greater number of warp-threads but are not interwoven in the section containing fewer warp-threads; for instance the 25 warp-threads which are employed in weaving the marginal portions of the wide sections but are not interwoven in the narrow sections. The invention accomplishes such 30 object by obviating floating of said warp-threads alongside a section in which they are not interwoven throughout the length of the latter, from the rear end of one wide section to the front end of the next. The 35 portions of the said warp-threads which thus are floated alongside the sections in which they are not interwoven require to be trimmed away subsequent to the weaving, the portions thus trimmed away becoming 40 waste, which entails a considerable loss.

45 The invention is illustrated in a form of embodiment adapted for use in the production of suspender and brace webs and comprising the combination with main take-up devices which are operative to effect the taking-up of the web during the weaving of the wide strips, of auxiliary take-up devices which are operative to take up the succeeding narrow strip alone, and controlling

means for said main take-up devices where- 55 by the taking-up action of the latter is suspended upon the completion of a wide strip and caused to be resumed upon the comple- 60 tion of the succeeding narrow strip. Through the operation of the mechanism comprising 65 such combination the drawing forward of the warp-threads which are not used in weaving the narrow strip is suspended during the production of such strip, thereby avoiding 70 the formation of long floats and practically 75 eliminating the loss in waste.

Fig. 1 is an isometric view of the illus- 80 trative embodiment aforesaid of the invention, including certain parts of a loom to which the said embodiment is supposed to 85 be applied.

Fig. 2 is a view in vertical section in a 90 plane parallel with the loom sides, showing certain additional parts.

Fig. 3 is a partly sectional view of the 95 auxiliary take-up devices, and parts asso- 100 ciated therewith, looking from the left in Fig. 1.

Fig. 4 is a rear view of the parts shown in Fig. 3, but with the lay omitted.

105 The main take-up devices shown in Figs. 1 and 2 comprise the take-up roll 1, fur- 110 nished with points or teeth for engagement with the web, and also having combined with it the worm-gear 2; the actuating worm 3, 115 which engages with the said worm-gear, the upright worm-shaft 4, the ratchet-wheel 5, Fig. 2, fixed on the said worm-shaft, and the 120 actuating pawl 6, the operating means for 125 which may be as approved in practice; and 130 the presser-roll 7, between which and the 135 take-up roll 1 the web passes after extend- 140 ing partly around the roll 1, the journals 8 145 of the said presser-roll 7 being confined as 150 usual between the opposite side-portions of 155 guide-pieces 9 attached to the breast-beam 10.

160 The main take-up devices act as usual during the weaving of a wide portion *a* of the web to feed forward the web as fast as the 165 said portion is woven, and in doing so they 170 operate to draw forward from the sources 175 of supply all of the warp-threads which enter into the production of the web.

180 A lay-beam is indicated at 11 in Fig. 2, 185 a reed carried thereby being indicated at 190 12, and at 13 is the front confining plate 195 at the top of the reed.

The auxiliary take-up devices comprise

the pair of rolls 14, 14, mounted in bearings in connection with the stand 15 fixed upon the top of the breast-beam 10. These rolls are located a short distance in front of the cloth-making point or fell, and the web as woven passes between them. The rolls 14, 14 are provided with points or teeth to engage with the web, and they are provided with intermeshing gears 16, 16, to cause them to turn in unison; they are actuated by means of a ratchet-wheel 17 fixed upon the shaft of the lower roll, a pawl 18, and a swinging pawl-carrier 19 which is hung upon the shaft of the lower roll, and to which the pawl 18 is pivoted at 20. The pawl 18 is held in engagement with the teeth of the ratchet-wheel 17 by means of a spring 21. The pawl-carrier 19 is furnished with an adjustable contact piece 22 with which the plate 13 engages in the forward stroke of the lay, so as thereby to actuate the pawl-carrier and the pawl 18, so as to rotate the feed-rolls. Reverse turning movement of the feed-rolls is prevented by means of a holding pawl 23, which is pivoted to stand 15 upon a screw 24, and held by a spring 25 in engagement with the teeth of the ratchet-wheel 17.

At 26 is a guide upon the front of the stand 15, to which the web passes from the rolls 14, 14, and around which the web changes direction on its way to the main take-up roll 1.

During the weaving of a wide section *a*, the main take-up devices act in usual manner to draw the web forward as fast as it is woven, and at this time the worm-shaft 4 is rotated by means of the actuating pawl 6; meanwhile the auxiliary take-up devices are actuated concurrently with the main take-up devices.

After the completion of the said wide section *a*, and while the leading portion of the next succeeding narrow portion *b* of web is being woven, the main take-up devices continue in action until the rear ends of the opposite side-portions of the wide section *a* have been drawn forward past the rolls 14, 14. Thereupon the actuation of the main take-up devices is suspended by means of the pattern-devices of the loom, acting for instance through cord 27, Fig. 3, to lift pawl 6 out of engagement with ratchet-wheel 5. Thereby the feeding forward of the wide section *a*, and of the warp-threads extending rearward from its rear end at the opposite sides of the narrow section *b* is suspended, but the actuation of the rolls 14, 14, by means of the described devices continues. Consequently the feeding forward of the narrow section *b* continues, the

said section being pushed forward in a loop above the wide section, as illustrated in Fig. 2. In the turning of the rolls 14, 14, the engagement of their teeth with the woven portion of the narrow strip serves to cause the latter to be taken up, but the said teeth move through the unwoven warp-threads at the sides of such section without advancing such threads. Upon the completion of the required length of narrow strip *b*, the pattern-devices bring about re-engagement of pawl 6 with ratchet-wheel 5, and the actuation of the main take-up devices is resumed while the next wide section of web is being woven.

What is claimed as the invention is,—

1. In loom mechanism for weaving a web comprising a section in which a given number of warp-threads is interwoven and a succeeding section in which a smaller number of warp-threads is interwoven, or vice versa, the combination with main take-up devices which are operative to effect the taking up the web during the weaving of the former section, of auxiliary take-up devices including a roll having teeth which during the weaving of the succeeding section pass idly between the non-woven warp-threads and act to take up only the woven material of such section, and controlling means for the main take-up devices whereby the taking-up action of the main take-up devices is suspended upon the completion of a section containing the full number of warp-threads and caused to be resumed upon the completion of the succeeding section containing fewer warp-threads.

2. In loom mechanism for weaving a web composed of wide and narrow web-sections alternately succeeding one another, the combination with main take-up devices which are operative to effect the taking-up of the web during the weaving of the wide sections, of auxiliary take-up devices which are operative to take up the succeeding narrow section alone, comprising a pair of toothed take-up rolls arranged close to the cloth making point or fell, and means for actuating said rolls, and controlling means for said main take-up devices whereby the taking-up action of the latter is suspended upon the completion of a wide section and caused to be resumed upon the completion of the succeeding narrow section.

In testimony whereof I affix my signature in presence of two witnesses.

GEORGE W. SPALDING.
